UNITED STATES PATENT OFFICE.

EDWARD FLANAGAN WOODSIDE, OF PELZER, SOUTH CAROLINA.

GAME-BOARD.

SPECIFICATION forming part of Letters Patent No. 693,478, dated February 18, 1902.

Application filed November 13, 1901. Serial No. 82,159. (No model.)

To all whom it may concern:

Be it known that I, EDWARD FLANAGAN WOODSIDE, a citizen of the United States, residing at Pelzer, Anderson county, South Carolina, have invented certain new and useful Improvements in Game-Boards, of which the following is a specification.

My invention relates to improvements in chance-controlled game apparatus, and is designed to provide an improved form of board for playing parlor base-ball.

The invention consists in providing a board or dial with inner and outer concentric circles or rings having spaces bearing designations of the plays to be made, the outer space bearing lines leading or pointing to the spaces or designations of the inner ring or circle.

The invention also includes the details of arrangement hereinafter described and claimed.

I have illustrated the invention in the accompanying drawing, which is a plan view of a board constructed in accordance with my improvement.

In the drawing is shown a board having two sections A and B, the latter section bearing the representation of a diamond; but as this forms no part of the present invention further description thereof is deemed unnecessary. On the other section A is arranged a dial C, having inner and outer concentric circles or rings C' and C², bearing descriptive words indicating the various plays. The inner circle is divided by a plurality of radial lines c' into spaces, within which are the descriptive phrases of this circle, and the outer circle is also divided by radial lines c² and c³ into spaces bearing descriptive words. The lines c² are extended to the line of division between the two circles, while the intermediate lines c³ are shorter, as shown. The line of division between the two circles is preferably a zigzag line, as indicated at c⁴, connecting the outer ends of the lines c' with the inner ends of the lines c². The inner spaces between the lines c' bear descriptive words or phrases designating the various plays, as also do the spaces between the lines c² and c³, while in the space at the inner end of each shorter line c³ appears the word "Foul." It will be seen that

the longer lines c² are arranged centrally of the spaces between the inner lines c' for the purpose hereinafter described.

A hand or pointer, preferably of thin light material, is mounted to rotate freely upon the center of the board, its slender point traveling over the outer circle.

Pieces or men are used in connection with the field shown on section B, and the arrow is rotated to determine the plays by giving it a sharp turn and letting it rotate until it comes to rest.

If the point comes to rest on any of the spaces between lines c² and c³, the play indicated by said space is made, while if it comes to rest on a short line c³ a foul is indicated. If, however, the point comes to rest on the long line, then the play to be made is indicated on the space on the inner circle to which said line points.

Having thus described my invention, what I claim is—

1. In a game of the class described, a dial comprising inner and outer concentric circles, radially-extending lines on said inner circle forming spaces bearing designations, radially-extending lines on said outer circle arranged centrally of the lines of the inner circle, shorter lines intermediate of said centrally-arranged lines and a rotary pointer having its point arranged to travel over the outer circle, substantially as described.

2. In a game of the class described, a dial comprising inner and outer concentric circles, radially-extending lines on said inner circle forming spaces bearing designations, radially-extending lines on said outer circle arranged centrally of the lines of the inner circle, shorter lines intermediate of said centrally-arranged lines, designations at the inner extremities of said shorter lines, and a rotary pointer having its point arranged to travel over the outer circle, substantially as described.

In testimony whereof I affix my signature in presence of two witnesses.

EDWARD FLANAGAN WOODSIDE.

Witnesses:

F. J. INGLESBY,
FRANCIS J. PELZER, 3d.
